UNITED STATES PATENT OFFICE.

CHARLES H. SAMPSON, OF ROCHESTER, NEW YORK, ASSIGNOR TO PEERLESS CHECK PROTECTING COMPANY, OF ROCHESTER, NEW YORK, A CORPORATION OF NEW YORK.

DESIGN FOR A CASING FOR CHECK-PRINTING APPARATUS.

44,587.

Specification for Design.

Patented Aug. 26, 1913.

Application filed June 13, 1913. Serial No. 773,554. Term of patent 14 years.

To all whom it may concern:

Be it known that I, CHARLES H. SAMPSON, a citizen of the United States, residing at Rochester, in the county of Monroe and State of New York, have invented a new, original, and ornamental Design for Casings for Check-Printing Apparatus, of which the following is a specification, reference being had to the accompanying drawing, forming part thereof.

Figure 1 is a top view of the casing for

check printing apparatus; Fig. 2 is a front view of the casing; and Figs. 3 and 4 are elevations of opposite sides of the apparatus.

I claim:

The ornamental design for a casing for a check printing apparatus, as shown.

CHARLES H. SAMPSON.

Witnesses:

HAROLD H. SIMMS,

ADA M. WHITMORE.
